UNITED STATES PATENT OFFICE.

EDWARD MOHUN, OF VICTORIA, BRITISH COLUMBIA, CANADA.

METAL-REINFORCED CONCRETE PILE.

958,967.

Specification of Letters Patent. Patented May 24, 1910

Application filed September 29, 1909. Serial No. 520,166.

To all whom it may concern:

Be it known that I, EDWARD MOHUN, a citizen of the Dominion of Canada, residing at Victoria, in the Province of British Columbia, Canada, have invented a new and useful Metal-Reinforced Concrete Pile, of which the following is a specification.

This invention relates to a metal reinforced concrete pile in which the metal used is of such form and is so distributed as to afford a maximum of strength to properly reinforce the material of the concrete with a minimum of weight. In carrying out this idea I make use of standard sections of angle iron or steel for the longitudinal reinforcing members, as such are not only easier to obtain but can be better joined together by cover angles where a greater length of the pile is required than the length of iron obtainable. In cross section of the pile the metal is also better distributed than where rods of iron or steel are used. Outside of these longitudinal members I place open mesh expanded metal through which the concrete of the outer side is effectually bonded with that within the metal reinforcement.

It must be distinctly understood that this pile is not one wherein the strength of the metal is itself sufficient to bear the load to be imposed upon it, and the concrete or cement is applied merely to protect the metal from corrosion; but is distinctly a concrete pile reinforced with metal to impart a greater strength under flexure such as a pile structure may be exposed to.

The invention is particularly described in the following specification, reference being made to the drawings with which it is accompanied, in which:

Figure 1 shows a vertical section of the upper end of the pile, Fig. 2, a portion of the mid-length of the pile showing the reinforcing frame in elevation, and Fig. 3, a vertical section showing the junction of the reinforcing frame to the foot of the pile, the outline of the concrete being indicated in the two last figures by dot and dash lines. Fig. 4 is a cross section on the line A A in Fig. 2 and Fig. 5, a cross sectional plan on the line B B in Fig. 3 and Fig. 6, a perspective view of a corner of the reinforcing frame adjacent to one of the cross frames showing the method of tying the expanded metal to the corner angle irons and to the cross frames.

The drawings show the application of my

system of construction to a pile of that class having a jet pipe through which water under pressure may be delivered to the lower end to sink the pile; but the structure 60 of the reinforcing frame may be used in a bearing pile for driving, or in a sheet pile or other structure where similar requirements exist.

In these drawings 2 represents the jet pipe 65 extending lengthwise of the pile, which jet pipe is connected outward at 3 to the side of the pile for connection to an hydraulic pressure service, and at 4 is reduced to a nozzle and secured in the bottom shoe of the pile. 70 To the upper end of the pile is secured a bolt 5 by which a timber superstructure may be attached to the pile, which bolt is furnished with an anchoring flange 6 to afford it a secure hold of the concrete. Freely fitted on this jet pipe 2 at intervals of approximately eight feet apart are a series of light cast iron cross frames 10 which frames conform to the cross section of the pile but are smaller in diameter to afford the necessary 80 thickness of concrete outside of the metal structure to preclude the possibility of it breaking from that structure in use. The dimensions of the metal reinforcing frame in relation to the pile need not be according 85 to the scale shown in the drawings as the structure of the frame is such as to bond the concrete outside of the frame effectually with that inside the frame, so that the cross section of the frame may be much greater in 90 proportion to the cross section dimension of the pile than is here shown.

The cross frames 10, the form of which is clearly shown in Fig. 5, have provision for the reception of angle irons 11 which extend 95 continuously from the shoe 5 to within a short distance of the top, and where the length of the pile required is in excess of the length of angle iron or steel available the continuity is preserved by a butt joint and 100 cover angles at each joint of the angle iron or in any other approved manner. These angle irons 11 fit freely in the recesses provided for them in the cross frames 10 and may be secured tightly in these recesses by 105 wedges 12 of soft metal such as horse shoe nails by which the angle irons are driven closely into the outer corners of the recesses.

The cross frames 10 are designed to maintain both the jet pipe 2 and the longitudinal angle irons 11 in position in relation to one another while the concrete is being

filled in and packed about the structure of the reinforcing frame.

Around the longitudinal angle irons between each pair of cross frames 10, open 5 mesh expanded metal 13 is placed and is securely tied by wire at 14 to the angle irons, and at 15 to the cross frames 10 and to the adjacent lengths of the expanded metal. These ties bind the expanded metal sheets to 10 each other and to the angle irons and hold them in their respective positions while the concrete is being filled and packed. The ties 15 are of equivalent cross sectional area to that of the expanded metal so that the 15 continuity of the expanded metal is effectively preserved throughout the length of the pile.

The bottom shoe 8 is made of sheet metal in the form of a truncated pyramid and the 20 bottom cross frame 10 rests upon portions 16 split and inwardly bent from the sides. The cross frame is centered on its supports 16 within the shoe by metal hooks 17 screwed into holes drilled in the supports. The angle irons 11 pass through the bottom frame 10 for a short distance and are anchored against the under side of the frame 10 by cross rods 18 through each adjacent pair.

When the reinforcing frame is complete 30 the concrete 9 is molded thereon preferably while the frame is in a horizontal position as by that means it can more quickly and effectively be packed to thoroughly fill in between the various parts of the metal structure.

The principal advantages of this method of construction, wherein angle irons and expanded metal are used to reinforce a concrete pile, are that the metal is of a form 40 that is readily obtainable, and its cross sectional area is such that it can be arranged that that area is distributed toward the outside of the pile and while its surfaces are sufficiently ample to afford a good surface to 45 the concrete those surfaces are not so uni-

formly plane that the concrete will readily break from it, as the expanded metal enables the concrete outside of the frame to be strongly bonded with that in the inside of the frame.

Having now particularly described my invention and explained the reason therefor, I hereby declare that what I claim as new and desire to be protected in by Letters Patent, is:

1. In a concrete pile, a plurality of angle irons running throughout the length of the pile, a series of spacing frames having apertures to permit passage of said angle irons and form seats therefor, expanded metal 60 members wound around said angle irons between said spacing frames, means for tying said metal members to said angle irons and to said spacing frames, a sheet metal shoe laterally extended to the outside diameters 65 of the pile and having cut portions inwardly bent, and means for securing one of said spacing frames to said inwardly bent portions.

2. In a concrete pile, a plurality of angle 70 irons running throughout the length of the pile, a series of spacing frames having apertures to permit passage of said angle irons and form seats therefor, expanded metal members wound around said angle irons between 75 said spacing frames, each of said spacing frames comprising an outer rectangular portion and diametrically disposed cross portions merging with a central apertured portion and a pipe within the pile projected through said apertured portions of 80 said spacing frames.

In testimony whereof I have signed my name to this specification in the presence of two subscribing witnesses.

EDWARD MOHUN.
